UNITED STATES PATENT OFFICE.

CHARLES H. GUNN, OF EMERYVILLE, CALIFORNIA, ASSIGNEE OF ONE-NINTH TO C. H. BLACK, OF OAKLAND, CALIFORNIA, AND ONE-NINTH TO F. O. NEBEKER, OF OAKLAND, CALIFORNIA.

TOILET FLUSH.

1,407,998.

Specification of Letters Patent. Patented Feb. 28, 1922.

Application filed September 24, 1919. Serial No. 326,016.

To all whom it may concern:

Be it known that I, CHARLES H. GUNN, a citizen of the United States, residing at Emeryville, county of Alameda, State of California, have invented certain new and useful Improvements in Toilet Flushes; and I do declare the following to be a full, clear, and exact description of the same, reference being had to the accompanying drawings, 10 and to the characters of reference marked thereon, which form a part of this application.

This invention relates to improvements in toilet flushing systems, the principal object 15 of the invention being to produce a device for the purpose which will utilize the direct pressure in the ordinary water pipes without the use or necessity of employing ball float or other forms of controlling valves 20 in the flushing tank or reservoir to regulate the flow of water thereinto, and in which the flushing action of the water is aided by a cushion of compressed air.

Another object is to provide a double or 25 divided tank with inflow and discharge means so coordinated in operation that while the contents of one portion of the tank are being discharged into the bowl of the toilet, the other compartment is receiving a fresh 30 supply of water.

Another object is to so arrange and combine the above indicated means that a single 35 movement of a hand lever in either direction will at once cause a flushing and filling operation to take place, this single lever movement being all that is necessary for the user of the toilet to do.

Another benefit of my device is the fact 40 that there are no rubber or similar composition valves to become worn or deranged, and no parts which can stick or refuse to function and cause the flushing tank to overflow, and cause a constant trickle of water into the 45 toilet bowl, such as frequently occurs with the present construction of toilet flushes.

The fact that there can be no great leakage 50 of water into the bowl under any conditions will be especially appreciated by those whose amount of water used and to be paid for is regulated by a meter.

A further object of the invention is to produce a simple and inexpensive device and yet one which will be exceedingly effective for the purposes for which it is designed.

55 These objects I accomplish by means of

such structure and relative arrangement of parts as will fully appear by a perusal of the following specification and claims.

In the drawings similar characters of reference indicate corresponding parts in the 60 several views.

Fig. 1 is a side elevation of a toilet showing my improved flush connected thereto.

Fig. 2 is a longitudinal section through the intake and discharge valve. 65

Fig. 3 is a top plan view of the same, detached from the tank.

Fig. 4 is a cross section through the discharge ports of the valve taken on a line 4—4 of Fig. 2. 70

Fig. 5 is a similar view through the inlet ports taken on a line 5—5 of Fig. 2.

Referring now more particularly to the characters of reference on the drawings, the numeral 1 denotes an air tight tank, preferably of cast iron and of suitable dimensions, and provided with a transverse wall 2 dividing the tank into two equal and non-communicating chambers 3 and 4. 75

Rectangular ports 5 and 6 are provided in 80 the bottom of the chambers 3 and 4 respectively, these ports being parallel and positioned close to the division wall 2, and being relatively long compared to their width.

These ports register with similar ports 7 and 8 provided in the upper portion of a 85 valve body 9, the latter having a flanged face 10 whereby it may be secured to the bottom of the tank.

Turnable in the body member 9 below the 90 ports 7 and 8 and extending lengthwise of and centrally between the same is a tapered valve member 11, which is hollow, such hollow portion being divided by a wall 12 into two separate compartments 13 and 14. 95

The compartment 13 is somewhat smaller than the compartment 14, and is provided with three ports 15, 16 and 17, ports 15 and 17 being substantially diametrically opposed, and port 16 intermediate thereto. 100 Either one of the ports 15 or 16 at a time is adapted to register with an intake port 18 provided in the side of the body member 9, this port being adapted for connection to a water pipe 19 leading from any suitable 105 source of pressure supply.

The ports 15, 16, and 17 are positioned relative to each other and to the ports 7 and 8 in the body so that when the port 15 is in register with the intake port 18, the port 16 110

will then align with the port 7 leading to one of the tank chambers the port 17 being then blanked, while when the valve 11 is turned in a manner hereinafter described, 5 the port 16 will register with the intake port 18, while the port 17 will register with the port 8 leading to the other tank chamber, the port 15 then being blanked.

The compartment 14 is provided with two 10 diametrically opposed ports 20 and 21, the port 20 being adapted to register with either at a time of the ports 7 and 8, while the port 21 registers at all times with a large outlet 22 in the bottom of the body 9, this outlet 15 being adapted for connection to the water flush pipe 23 of the toilet 24.

The ports 20 and 21 are positioned relative to the ports 15 and 16 and 17 so that when communication is open from the pipe 20 19 to the port 7 and chamber 3, the port 20 is then in communication with the port 8 leading to the chamber 4, and vice-versa.

A cupped cap 25 is screwed into the end of the body 9 adjacent the large end of the 25 valve 11 therein and spaced somewhat therefrom. A helical spring 26 bears against the inner face of the cap at one end, the other end seating in a cup 27 having a pointed lug 27^a on the outside and central thereof adapted to 30 seat in a V-shaped hole 28 provided in the end wall of the valve member 11. By this means, while the full pressure of the spring is exerted against the valve to seat the same and prevent longitudinal movement, when 35 the valve is turned, the full area of the end of the spring is not binding against the end wall of the valve to increase the frictional resistance of turning.

The other end of the valve 11 is provided 40 with a stem 29 projecting beyond the body 9, on which stem is secured a hand lever 30 suitably curved to bring the handle 31 thereof within easy reach of the operator.

In order to limit the range of movement 45 of this lever, the hub 30^a thereof has a lug 32 projecting somewhat over the small end 9^a of the body member 9, and adapted to abut against lugs 33 thereon, these lugs being spaced apart the necessary distance to 50 give freedom of movement of the valve 11 between the two different settings of the ports therein.

The operation of the device will now be 55 evident from the foregoing description, all the figures on the drawings showing the valve 11 in the same position, that is with the lever 30 in its upmost position. In this position, referring to Fig. 5, water is being admitted to the chamber 3 through ports 7, 60 16, and 15 from the water pipe 19.

At the same time, referring to Fig. 4, the compartment 4 is being emptied of its contents to flush the toilet through ports 8, 20, 65 and 21. As soon therefore, as the lever 30 is moved to this upmost position, the cham-

ber 3 will start to fill, and the chamber 4 to empty.

When it is desired to again flush the toilet, the lever is moved down, the position of the ports in the valve is reversed and the chamber 4 then fills while the chamber 3 empties. The empty chamber 4 however contains air, 70 which is compressed by the pressure of the incoming water, and as it cannot escape, it is held in the chamber and acts to force the 75 water out, when the lever is turned to flush that compartment, with a greater force than it would otherwise have.

From the foregoing description it will be 80 readily seen that I have produced such a device as substantially fulfills the object of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what 90 I claim as new and useful and desire to secure by Letters Patent is:

1. A valve comprising a casing having a pair of transversely spaced ports therein, a discharge port opposite to said first named ports, an intake port positioned between said other ports, a cylindrical member rotatably mounted in the casing and adapted to be turned by hand, a transverse division wall in the cylindrical member, the latter 100 being hollow; and ports in each of the chambers thus formed; one of the ports in one chamber being adapted to register with the intake port in the casing while another port registers with one of said first named casing 105 ports, said last-named chamber-port being adapted to register with the intake port while another port in said chamber registers with the other one of said first named casing-ports, and one of the ports in the 110 other chamber being adapted to constantly register with the discharge port in the casing while the other port is in alignment with either one of the first named ports in opposed order to the registering there- 115 with of the port in the other chamber.

2. A valve comprising a casing having a pair of transversely spaced ports therein, a discharge port opposite to said first named ports, an intake port positioned between said other ports, a hollow cylindrical member turnably mounted in the casing, and a transverse division wall in the hollow member dividing the same into two compartments, one of said compartments being arranged for constant communication with the intake port in the casing and alternately with the first named of the casing ports, and the other compartment being arranged for constant communication with the dis- 120 125 130

charge port in the casing and alternately with the first named casing ports in reverse order to the other compartment.

3. A valve comprising a casing having a pair of transversely spaced ports therein, a discharge port opposite to said first named ports, an intake port positioned between said other ports, a cylindrical member rotatably mounted in the casing, and longitudinally spaced passage means through said member, certain of said passage means being arranged to allow constant communication from the intake port in the casing to the

first named of the casing ports alternately, and the other passage means being arranged to allow constant communication between the discharge port in the casing and with the first named casing ports alternately and in reverse order to the alignment therewith of the first passage means.

In testimony whereof I affix my signature in presence of two witnesses.

CHARLES H. GUNN.
